UNITED STATES PATENT OFFICE.

GEORGES ZIËGLER, OF PARIS, FRANCE.

TYPE-WRITING MACHINE.

1,098,605.

Specification of Letters Patent.

Patented June 2, 1914.

Application filed November 20, 1911. Serial No. 661,364.

To all whom it may concern:

Be it known that I, GEORGES ZIËGLER, a citizen of the Republic of France, residing at Paris, France, have invented new and useful Improvements in Type-Writing Machines, of which the following is a specification.

My invention relates to typewriters and more particularly to that class of machine in which a single element is used to carry the type characters.

My invention provides a typewriter of the class mentioned in which the mechanism for operating the element carrying the type characters is of extremely simple construction and comprises a minimum number of parts, without sacrificing the efficiency of the machine in any particular, but on the other hand increasing the rapidity with which it may be operated.

In the drawing annexed hereto and forming a part of this specification: Figure 1 is a diagrammatic illustration of the elements which coöperate to bring the type characters into contact with the paper or other material to be printed on. Fig. 2 illustrates the relation of the key stem to the helically twisted portion of the axle carrying the element bearing the type characters, when the keys are in the normal position. Fig. 3 illustrates the relation of the key stem to the helically twisted portion of the axle carrying the element bearing the type characters, when one key is in the depressed position. Fig. 4 illustrates a practical embodiment of my invention in a typewriting machine. Fig. 5 is a section on the line X—X of Fig. 4.

Referring to the drawings in which like characters of reference designate similar parts. In Fig. 1, which shows diagrammatically the relation of the members co-operating to operate the element bearing the type characters, 1 is a semi-cylindrical member, carrying on its curved periphery a multiplicity of type characters. The member 1 is carried by an axle 2 having a flattened portion 3 between its ends, said flattened portion being twisted so as to present a helical surface; at the end of the axle 3 is carried a ball 4 or other member by which the said axle may be journaled in the carriage frame of the typewriting machine so as to allow universal movement. The members 5 represent the stems of the keys indicated at 13 in Fig. 4 and which in their depressed position contact with the helical

surface of the flattened portion 3 of the axle and serving to rotate the said flattened portion and member 1, at the same time depressing the type carrying member 1 until it contacts with the paper 6 or other material to be printed on. The rotating of the axle serves to bring the particular type character represented by the key depressed into position to print on the paper when the type carrying member comes in contact therewith. In Fig. 2 it will be observed that the stem of the key is in its normal position and that the flattened portion of the axle lies at an angle to the bottom of the stem; while in Fig. 3 the key is shown in a depressed position required for printing and the axle has rotated until the stem of the key lies with its bottom portion flat against the helical surface of the flattened portion.

Referring particularly to Figs. 4 and 5 in which I have illustrated a practical embodiment of my invention; 7 is a carriage frame slidable longitudinally on the base 8 and guided by the tracks 9. Mounted transversely of the carriage frame 7 is the axle 2 having the twisted flattened portion 3 and journaled at the rear end in the socket 10, or in any other suitable manner allowing universal movement, this mounting not comprising part of the present invention. The forward end of the axle extends through the slot 11 in the vertical wall of the carriage frame and carries the semi-cylindrical type bearing member 1 which is directly over a suitable member adapted to hold the paper 6 or material adapted to be printed on. The axle 2 is resiliently supported at the forward end by the spring 12 which raises it to its normal position after having been depressed for printing. In the top plate of the carriage frame is arranged a series of keys 13 each one representing a particular type character on the member 1, and adapted when depressed to contact the stem 5 carried thereby at a certain point with the helical surface of the portion 3 so as to cause the member 1 to rotate and bring into the proper position to imprint the type character, which it represents, on the paper 6. The keys 13 carry on their stems above the top plate of the carriage frame suitable means such as springs 15 to return them to their normal position after being depressed and are also prevented from moving too far upwardly by means of the pins 16 contacting with the

under surface of the top plate of the carriage. Arranged on the base 8 is a suitable member 14 adapted to carry the paper 6 or other material to be printed on, but as 5 this member comprises no part of my invention it is not necessary to describe it in particular, and any other suitable member having the same function may be substituted therefor.

10 It is understood that I do not limit myself to the precise construction and arrangement of parts herein illustrated and described, but may resort to such modifications as fall within the scope of my claim.

15 I claim:

The combination in a typewriting machine, of a semi-cylindrical type carrying member, of an axle carrying said type car-

rying member mounted to permit universal movement, and having a flattened portion 20 midway between its ends presenting a helical surface, of compressible keys having stems adapted to engage the helical surface of said flattened portion of the axle and cause the 25 type carrying member to rotate, whereby the type character representing the particular key depressed is brought into position to imprint and at the same time depress the axle downward toward the paper or other material to be printed on.

30 In testimony whereof I affix my signature in presence of two witnesses.

GEORGES ZIÉGLER.
